CLAIM

The ornamental design for a combined motor housing and blade irons unit for an electric ceiling fan, as shown and described.

DESCRIPTION

FIG. 1 is a perspective view of a combined motor housing and blade irons unit for an electric ceiling fan;

FIG. 2 is an enlarged side elevational view thereof, the opposite side being a mirror image of that shown;

FIG. 3 is an enlarged bottom plan view thereof; and,

FIG. 4 is an enlarged top plan view thereof.

The broken line showing of environmental structure in FIGS. 1 and 2 is for illustrative purposes only and forms no part of the claimed design.
